UNITED STATES PATENT OFFICE.

WILLIAM ZAEHRINGER, OF NEW ORLEANS, LOUISIANA.

CALENDAR.

SPECIFICATION forming part of Letters Patent No. 788,746, dated May 2, 1905.

Application filed November 23, 1900. Renewed January 16, 1905. Serial No. 241,350.

To all whom it may concern:

Be it known that I, WILLIAM ZAEHRINGER, a citizen of the United States, residing at New Orleans, in the parish of Orleans and State of 5 Louisiana, have invented a new and useful Improvement in Calendars, of which the following is a specification.

The object of my invention is, first, to provide a calendar composed of and printed on 10 twelve sheets of paper and employing an index-hand pivoted at their centers, adapted to point out successively in a conspicuous manner the day of the current month and the day of the week simultaneously; second, a series 15 of twelve calendar-sheets each showing the varying number of days in each month, the serial number of each month, the age of the year in number of days up to the end of each month, and the months composing the four 20 seasons of the year; third, a series of twelve calendar-sheets each showing conspicuously the current year, month, and its serial number, and, fourth, a series of twelve calendar-sheets each containing the dates of all Sun- 25 days in the year apportioned to each month. These objects are attained with uncommon facility, owing to the novel and peculiar manner of grouping the figures and letters necessarily employed. All items of information 30 are conveyed at a glance and are comprehensive, as will be evident when reference is had to the annexed drawings, forming part of this specification.

Figure 1 represents the month of January 35 of the year 1901, to be printed on a sheet of paper, and will serve as a sample-sheet of the calendar. The eleven remaining months are not shown, as they are in most parts duplicates of the January sheet, and the differences 40 in their composition, as herein explained, will be readily understood. Fig. 2 is a vertical central section of the calendar shown in Fig. 1.

Obviously in composing this calendar the size of the sheets and the style of type to be 45 employed are optional. I shall therefore assume that the dimensions of a sheet are eight by eight inches, in which case I prefer that the apportionment of the spaces for the various items of information to be printed will be 50 as follows: A circular central space A is two

and one-half inches in diameter to contain the name "January," abbreviated to "Jan." in large type, and the figure "1" above and the figures "1901" below the month, as shown in Fig. 1. A circular space B, adjoining the central space A and separated by two parallel lines, having a maximum diameter of three and one-eighth inches, is divided into four equal parts, each part to contain the names of the respective seasons "Spring," "Summer," "Autumn," "Winter," as shown in Fig. 1. A circular space C, adjoining the space B and separated by one line, having a maximum diameter of three and five-eighths inches, is divided into twelve equal parts, each part to contain the age of the year in days up to and inclusive of the last day of each month as they are successively named in the next adjoining space, thus, "31, 59, 90, 120, 151, 181, 212, 243, 273, 304, 334, 365," as shown in Fig. 1. A circular space 55 D, adjoining the space C and separated by one line, having a maximum diameter of four and five-eighths inches, is divided into twelve equal parts to correspond with the last-named divisions, each part to contain, respectively, the 60 name of a month, abbreviated thus, "Jan.," "Feb.," "Mar.," "Apr.," "May," "Jun.," "Jul.," "Aug.," "Sep.," "Oct.," "Nov.," "Dec.," as shown in Fig. 1, and within the 65 same respective spaces the respective serial numbers of the months, "1, 2, 3, 4, 5, 6, 7, 8, 9, 10, 11, 12," as shown, and on the same imaginary circular line the number of days 70 belonging to each of the respective months, "31, 28, 31, 30, 31, 30, 31, 30, 31, 30, 31," 75 as shown in Fig. 1. A circular space E, adjoining the space D and separated by two parallel lines, having a maximum diameter of five and three-quarter inches, is divided into seven equal parts, each part to contain, respectively, the names of the successive days of the 80 week, "Monday," "Tuesday," "Wednesday," "Thursday," "Friday," "Saturday," and "Sunday," abbreviated thus, "Mon.," "Tue.," "Wed.," "Thu.," "Fri.," "Sat.," "Sun.," 85 as shown in Fig. 1. A circular space F, adjoining the space E and separated by one line, having a maximum diameter of seven inches and divided, to correspond 90 with the last divisions, into seven equal parts, 95 "Sun.," as shown in Fig. 1. A circular space G, adjoining the space F and separated by one line, having a maximum diameter of eight inches and divided, to correspond 100 with the last divisions, into seven equal parts,

- each part to contain, respectively, the figures representing all the days of the month which will fall on the successive days of the week, respectively, as follows: "7, 14, 21, 28," "1, 5 8, 15, 22, 29," "2, 9, 16, 23, 30," "3, 10, 17, 24, 31," "4, 11, 18, 25," "5, 12, 19, 26," "6, 13, 20, 27," as shown in Fig. 1. A circular space G, adjoining the space F and separated by two parallel lines, having a maximum diameter of seven and three-quarter inches to contain the word "Sundays" at its base and the respective names of the twelve months abbreviated, with the respective dates of each month which will fall on a Sunday following the same, thus, "Jan. 6, 13, 20, 27," "Feb. 3, 10, 17, 24," "Mar. 3, 10, 17, 24, 31," "Apr. 7, 14, 21, 28," "May 5, 12, 19, 26," "Jun. 2, 9, 16, 23, 30," "Jul. 7, 14, 21, 28," "Aug. 4, 11, 18, 25," "Sep. 1, 8, 15, 22, 29," "Oct. 6, 13, 20, 27," "Nov. 3, 10, 17, 24," "Dec. 1, 8, 15, 22, 29," as shown in Fig. 1.

It will be observed that the various spaces allotted for the item of information will admit the use of a variety and size of type calculated to give the greatest prominence to the most important matters of interest.

Holidays may be designated, as ordinarily, by the representative figure being printed in red ink or by its having a red star or other character printed across it or a sign printed conjointly with it.

It will be observed that the entire composition of a printed sheet will form a symmetrical dial in appearance and is divided into four main parts, respectively, by double parallel lines. Two of these parts are subdivided into various arc-sections and comprehensively connected, as shown in Fig. 1.

40 The series of calendar-sheets *h*, Figs. 1 and 2, are backed with a stiff piece of cardboard *L* and clamped firmly together with eyelets *r*, *s*, *t*, and *u* near each corner, as shown.

Fig. 2 shows the centrally-affixed stud *m* with a head *n*, the washer *o*, the index-hand *I*, the front disk *v*, the calendar-sheets *h*, the cardboard backing *L*, the rear disk *y*, and eyelets *r* and *t*.

In permanently affixing the index-hand *I*, Fig. 2, the stud *m* is first to be slipped through the metallic washer *o*, then through the hole in the butt-end of the index-hand *I*, then through the centers of the calendar-sheets *h* and the cardboard backing *L*, and, lastly, through the rear metallic disk *y*, after which the projecting end of the stud *m* is bent approximately at a right angle and down against the rear disk *y*, as shown, so that the necessary amount of pressure is brought to bear against the surfaces of the butt-end of the index-hand *I* by being clamped between the washer *o* on one side and the disk *v* on the other side, thus serving to hold it with reasonable firmness in the various positions required.

The core centers of the calendar-sheets *h*, Fig. 2, are used to form a permanent elastic pad *w* and are perforated in a circle having a diameter slightly in excess of the diameter of the metallic disk *v*, as indicated by the dotted lines *k* and *l*, to facilitate the removal of the calendar-sheets *h* one by one minus their core centers.

When a month has expired, its representative sheet must be torn away, leaving only small jagged portions of the same around the eyelets *r*, *s*, *t*, *u* and obviously around and slightly beyond the edge of the metallic disk *v*, Fig. 2, whereby the circular elastic pad *w*, formed by the core centers of the calendar-sheets *h*, remains intact approximately within the dotted lines *k* and *l* and yields a constant pressure against the disk *v*, which will serve to hold the index-hand *I* in any position required whether one or more of the calendar-sheets *h* have been torn away.

A knob may obviously be keyed to or form an integral part of the index-hand *I* to facilitate the rotation and setting of the same.

The sheet of cardboard backing *L* may be of a size and shape to admit of displaying upon one or more of its marginal sides advertisements, pictures, interesting printed matter, or other useful features.

Having described the composition of the January sheet, we will note the differences existing in the composition of eleven remaining sheets, as follows: First, the February sheet has the dates "29, 30, 31" removed from their respective arc-sections in the circular space *F*, and the remaining dates "1, 8, 15, 22," "2, 9, 16, 23," and "3, 10, 17, 24" are spread out in their respective arc-sections. All other dates in this circle are left intact as they now are. Secondly, as the first day of February will fall on a Friday the entire circle *E*, composing the days of the week, has been shifted so that the arc-section containing the letters "Fri." adjoins and corresponds with the arc-section containing the dates "1, 8, 15, 22." Thirdly, from the central space *A* the letters "Jan." have been removed and "Feb." substituted instead. Fourthly, the serial number of the month "1" has been removed from the central space *A* and "2" substituted instead. These are the only differences in the composition of the February from the January sheet. Hence I deem it unnecessary to show more than the component parts of the January sheet by drawings.

March differs from the January sheet as follows: The letters "Fri." are placed relatively to designate that Friday will be the first day of the said month, and the central space has the number "3" in place of "1" and the letters "Mar." in place of "Jan."

April differs from the January sheet as follows: The date "31" is removed from its arc-section and the dates "3, 10, 17, 24" are spread out in the said section. The letters "Mon."

are placed relatively to designate that Monday will be the first day of the said month, and the central space has number "4" in place of "1" and the letters "Apr." in place of 5 "Jan."

May differs from the January sheet as follows: The letters "Wed." are placed relatively to designate that Wednesday will be the first day of the said month, and the central space has number "5" in place of "1" and the letters "May" in place of "Jan."

June differs from the January sheet as follows: The date "31" is removed from its arc-section and the dates "3, 10, 17, 24" are spread out in the said section. The letters "Sat." are placed relatively to designate that Saturday will be the first day of the said month, and the central space has number "6" in place of 15 "1" and the letters "Jun." in place of 20 "Jan."

July differs from the January sheet as follows: The letters "Mon." are placed relatively to designate that Monday will be the first day of the said month, and the central 25 space has number "7" in place of "1" and the letters "Jul." in place of "Jan."

August differs from the January sheet as follows: The letters "Thu." are placed relatively to designate that Thursday will be the first day of the said month, and the central 30 space has number "8" in place of "1" and the letters "Aug." in place of "Jan."

September differs from the January sheet as follows: The date "31" is removed from its 35 arc-section, and the dates "3, 10, 17, 24" are spread out in the said section. The letters "Sun." are placed relatively to designate that Sunday will be the first day of the said month, and the central space has number "9" in place 40 of "1" and the letters "Sep." in place of "Jan."

October differs from the January sheet as follows: The central space has number "10" in place of "1" and the letters "Oct." in place 45 of "Jan."

November differs from the January sheet as follows: The date "31" is removed from its arc-section, and the dates "3, 10, 17, 24" are spread out in the said section. The letters "Fri." are placed relatively to designate that Friday will be the first day of the said month, and the central space has number "11" in place of "1" and the letters "Nov." in place of "Jan."

December differs from the January sheet as follows: The letters "Sun." are placed relatively to designate that Sunday will be the first day of the said month, and the central space has number "12" in place of "1" and the letters "Dec." in place of "Jan."

It will be evident that the changes required in the composition of matter for printing the several calendar-sheets are few and simple, for the reason that about five-sixths of the entire matter composing the January sheet, as

shown in Fig. 1, must always remain intact for repeated impressions in conjunction with the minor changes, as described.

The calendar-sheets for a leap-year will obviously require the following changes in their composition: The numbers now in the circle C for showing the age of the year at the end of each month must all be removed from their respective arc-sections excepting number "31," the January section, and substituted, 70 respectively, by numbers "60, 91, 121, 152, 182, 213, 244, 274, 305, 335, 366" for printing each of the twelve monthly sheets. The name and numbers "Feb. 2, 28," now in one of the arc-sections of the circle D, must be made to 75 read "Feb. 2, 29" for printing each of the twelve monthly sheets. When printing the February sheets, the date "29" must be left remaining in its respective arc-section of the circle F.

The entire composition of the sheets may optionally be printed in two or more colors for the purpose of giving greater prominence to the most important items of information. For this purpose I would suggest that all the 80 composition in the central space A and a single border-line be printed in black, all the composition in the combined circular spaces B, C, and D and their straight and curved lines in red, all the composition in the combined circular spaces E and F and their straight and curved lines in black, and all the composition in the circular space G and its curved lines in red.

By referring to the extreme outer circle of 85 the January sheet for 1901, which contains the abbreviated names of each successive month and the dates of their respective Sundays, it can readily be ascertained upon which day of the week the 16th day of May will 90 fall. The inspection will disclose the fact that the 12th day of May will fall on a Sunday, and consequently the 16th will fall on a Thursday. In like manner, supposing that in the month of December, 1901, we are inspecting the December sheet of this calendar 95 and desire to know which day of the week was the 8th day of January, the inspection will show that the 6th day of January was Sunday, and consequently the 8th must have 100 been Tuesday. Hence the composition in the circle G will readily serve to discover any past or future day of the month, with its corresponding day of the week, in a current year.

An inspection of the circle B and the circle 105 D will show, respectively, that the season "Spring" embraces March, April, and May. "Summer" embraces June, July, and August. "Autumn" embraces September, October, and November. "Winter" embraces 115 December, January, and February.

An inspection of the circle C shows the age of the year up to the end of each successive month in number of days.

From the foregoing description my inven- 120

tion can be fully understood without further comment or explanation.

I do not restrict myself to the employment of any particular size of sheets and the consequent allotment of the spaces for composing the calendar months as herein described. Several changes may be preferred—such as turning words or figures into other directions, transposing items in circles, &c. without 10 constituting a material difference in my invention, which is obviously susceptible of manifold modifications.

Having described my invention, what I claim as new, and desire to secure by Letters 15 Patent, is—

1. A calendar, consisting of a series of sheets of paper *h*, each having printed thereon, an annular space *F* divided into seven equal arc-spaces, each space containing a grouped series 20 of four or five necessary numerals to designate the successive dates of the respective Sundays, Mondays, Tuesdays, Wednesdays, Thursdays, Fridays, and Saturdays of a month, and readily show, in a group, the precise number 25 of Sundays, Mondays, Tuesdays, Wednesdays, Thursdays, Fridays, and Saturdays of the month; a conjoined annular space *E* divided into seven arc-spaces to correspond with the spaces of *F*, each space containing the abbreviated name of a day of the week; a central space *A* containing the abbreviated name of a month, its serial number, and the current year; an annular space *D* divided into twelve equal arc-spaces, each space containing the abbreviated name of a month, the respective serial number of a month, and the numerals to designate the respective number 30 of days allotted to a month; a conjoined annular space *G* divided into twelve arc-spaces to correspond with the spaces of *D*, each space containing a numeral to designate the age of the current year at the end of each successive month; a conjoined annular space *B* divided into four equal arc-spaces, each space containing the name of a season of the year, and respectively designating three of the twelve months in the annular space *D* as constituting a respective season; an annular space *C* containing the abbreviated name of each month and followed with numerals to designate the 35 respective dates of every Sunday allotted to each month of the year; the entire series of calendar-sheets *h* being mounted with eyelets *r*, *s*, *t*, and *u*, upon a sheet of cardboard backing *L*, and having combined therewith, a co-operative index-hand *I*, pivoted upon a permanently-affixed stud *m*, between a washer *o*, and a disk *v*, and having a rear disk *y*, between which and the disk *v*, are pressed and permanently retained, the perforated core 40 centers of the entire series of calendar-sheets *h* and the cardboard backing *L*, jointly forming an elastic pad *w*, and hence adapting the said index-hand *I* to be rotated, and set to point simultaneously to the current day of 45 the week and the current day of the month, and indicate at its pivoted end, the current month, its serial number, and the current year, substantially as, and for the pur- 50 poses set forth.
2. A calendar, consisting of a series of sheets of paper *h*, each having printed thereon, an annular space *F* divided into seven equal arc-spaces, each space containing a grouped series 55 of four or five necessary numerals to designate the successive dates of the respective

Sundays, Mondays, Tuesdays, Wednesdays, Thursdays, Fridays, and Saturdays of a month, and readily show, in a group, the precise number of Sundays, Mondays, Tuesdays, 60 Wednesdays, Thursdays, Fridays, and Saturdays of a month; a conjoined annular space *E* divided into seven arc-spaces to correspond with the spaces of *F*, each space containing the abbreviated name of a day of the week; 65 a central space *A* containing the abbreviated name of a month, its serial number, and the current year; an annular space *D* divided into twelve equal arc-spaces, each space containing the abbreviated name of a month, the respective serial number of a month, and the numerals to designate the respective number 70 of days allotted to a month; a conjoined annular space *G* divided into twelve arc-spaces to correspond with the spaces of *D*, each space containing a numeral to designate the age of the current year at the end of each successive month; a conjoined annular space *B* divided into four equal arc-spaces, each space containing the name of a season of the year, and respectively designating three of the twelve months in the annular space *D* as constituting a respective season; an annular space *C* containing the abbreviated name of each month and followed with numerals to designate the 75 respective dates of every Sunday allotted to each month of the year; the entire series of calendar-sheets *h* being mounted with eyelets *r*, *s*, *t*, and *u*, upon a sheet of cardboard backing *L*, and having combined therewith, a co-operative index-hand *I*, pivoted upon a permanently-affixed stud *m*, between a washer *o*, and a disk *v*, and having a rear disk *y*, between which and the disk *v*, are pressed and permanently retained, the perforated core 80 centers of the entire series of calendar-sheets *h* and the cardboard backing *L*, jointly forming an elastic pad *w*, and hence adapting the said index-hand *I* to be rotated, and set to point simultaneously to the current day of 85 the week and the current day of the month, and indicate at its pivoted end, the current month, its serial number, and the current year, substantially as, and for the purposes set forth.

In testimony whereof I have signed my 90 name, in the presence of two subscribing witnesses, to this specification.

WM. ZAEHRINGER.
